UNITED STATES PATENT OFFICE

FRIEDRICH W. F. BERGER, OF BERLIN, GERMANY, ASSIGNOR TO THE NATIONAL CASH REGISTER COMPANY, OF DAYTON, OHIO, A CORPORATION OF MARYLAND

CASH REGISTER

Application filed May 14, 1929. Serial No. 362,962.

This invention relates to improvements in registers and like machines, and is more particularly directed to controlling means for such machines.

5 For illustrative purposes, the invention is shown applied to a machine of the type disclosed in Letters Patent of the United States, No. 1,242,170, granted October 9, 1917, to F. L. Fuller, and No. 1,619,796, granted March 10, 1927, to B. M. Shipley.

Specifically, this invention is an improvement on the mechanism disclosed in Letters Patent of the United States, Number 1,736,067, granted November 19, 1929, to 15 Samuel Brand.

The patents mentioned above disclose a register or accounting machine of the key-set type equipped with the well known total control lever to condition the machine to make 20 "add", "sub-total", and "total" operations. This control lever, as disclosed in said patents, is manually set before the machine is released for operation and, after the completion of the operation, is manually restored 25 to its normal "add" position.

The Brand application discloses means to automatically restore the control lever to its normal or "add" position immediately at the 30 end of a "total" operation, which relieves the operator of this duty. Brand's mechanism, however, restores the control lever to "add" position at the completion of each total taking operation whether it is desired to do so or not, and the condition frequently 35 arises when the operator desires to make a series of "total" operations to successively clear the several totalizers with which machines of the type indicated are usually provided. The present invention contemplates 40 selective automatic restoration of the total control lever to its "add" position.

It is, therefore, an object of the present invention to provide a register or accounting 45 machine of the type indicated, with novel mechanism under control of the operator to determine the effectiveness of the automatic restoring means.

Another object is to provide a machine of 50 the type indicated with a key-controlled

means to disable an automatic control lever restoring means.

With these and incidental objects in view, the invention consists of certain novel features of construction and combinations of parts, the essential elements of which are set forth in appended claims and a preferred form or embodiment of which is hereinafter described with reference to the drawings which accompany and form a part of this specification.

In said drawings

Fig. 1 is a view in right elevation of the operating and controlling mechanism for the machine, embodying one convenient means to obtain the foregoing objects.

Fig. 2 is a detail view of the total control lever, with part of the mechanism operated thereby, and a part of the automatic restoring means for such lever.

Fig. 3 is a view in right elevation of a well-known form of key-controlled differential mechanism.

Fig. 4 is an enlarged detail view of the restoring segment for the total control lever.

Fig. 5 is a detail view in front elevation of the mechanism disclosed in Fig. 4.

Fig. 6 is a detail view of a modified form of mechanism for selectively controlling the automatic restoring means.

General description

The machine chosen to illustrate one form of the present invention, and which is fully disclosed in the above-mentioned patents, includes generally, a plurality of banks or rows of amount keys to enter amounts into one or more of a plurality of selected totalizers, a plurality of banks of control keys to select the totalizers and otherwise control the operation of the machine, indicators to indicate the amount and classification of the transaction registered in the machine, and a total control lever to position the machine to make "adding", "sub-totaling" or "totaling" operations. Several other elements are included in the general make-up of the machine, such as printing mechanism, special counters, etc., but since this invention is directed more particularly to automatic re-

storing means for the total control lever, and mechanism for controlling the restoring means, description and illustration of all elements not pertinent thereto are omitted 5 from this application.

In registers and accounting machines, such as are disclosed in the above-referred to patents, the amounts of the items or transactions entered into the machine are accumulated on 10 one or more of the totalizers selected under the control of clerks' or transaction keys, and the conditioning or total control lever. After a lapse of time, as for instance, at the end of each day, it is desired to take a total from 15 certain of the totalizers. These totalizers, in the particular type of machine chosen for illustrative purposes, are arranged in a plurality of groups, and the particular group from which it is desired to select a particular 20 totalizer to be cleared, is selected by manually moving the total control lever from its normal "add" position to a certain one of its several remaining positions, after which the appropriate transaction key is depressed 25 which sets mechanism to select a desired totalizer. The machine is then operated to select the desired totalizer and to take the total therefrom. After the operation of the machine, the total control lever, as disclosed in 30 the above-mentioned patents, may be manually returned to its adding position, or adjusted to another of its totalizing positions, or allowed to remain in its last position, depending upon the nature of the next succeeding operation, and the group from which 35 it is desired to select a particular totalizer for the operation.

The Brand patent, referred to above, discloses mechanism which, upon adjustment of 40 the total lever to a certain one of its totalizing positions, and operation of the machine, automatically returns the lever to its adding position at or near the end of the machine operation, regardless of the particular totalizer selected.

In the normal use of the machine, it is desired, at the end of a day's business, to clear all of the totalizers which have been selected during that day, under the control of the 50 banks of totalizer-selecting keys. In such cases, it is not desired that the total control lever return automatically to its "add" position after each totalizer is cleared, as to do so would only necessitate repositioning the 55 lever to the desired totalizing position before the next succeeding operation. For this reason mechanism is now provided to render ineffective the automatic restoring mechanism for the total lever at such times as the 60 operator desires to make successive totaling operations.

However, this type of register is usually constructed with a certain special key in the totalizer selecting bank which the operator 65 depresses whenever it is desired to list a plu-

rality of items, the total of which is desired immediately. This key is known as the "list" key and is usually located in the "1" position in the key bank. After the amounts of a group of items have been accumulated on the 70 totalizer selected under control of the "list" key, the total control lever is adjusted to the correct position for conditioning the machine to take the total of the "list" totalizer. Since this is the only totalizing operation to 75 be made at this time, it is desirable to have the automatic total lever restoring means effective to return the total lever to its "add" position.

Mechanism for selectively controlling the effectiveness of the automatic restoring mechanism for the total control lever constitutes the subject matter of the present invention and is fully described below.

Detail description

The total control lever 30 (Fig. 2) which conditions the machine for item entering and total taking operations, projects from a substantially circular control disk 31, pivoted on a stud 32, suitably supported in the machine. The total control lever 30-31 is shown in full lines in its "add" position, the dot-and-dash line in Fig. 2 indicating the first position of the lever below its "add" position, to which it is adjusted when printing the total of the amounts accumulated by listing operations. The various mechanisms adjusted by movement of the total control lever 30 to its "total" position for conditioning the machine to make a totalizing operation, are only partially disclosed herein and for a full and complete understanding thereof, reference may be had to the above-mentioned patents.

The usual drive shaft 33 is journaled in a right side frame 34 (Fig. 1) and a left side frame 35 (Fig. 3) of the machine. This shaft makes one rotation in a clockwise direction, as viewed in Figures 1 and 3, at each adding operation of the machine, and two rotations in the same direction, at each total-taking operation, for reason well known in the art, and which are fully set forth in the above-mentioned patents. Any suitable means may be employed to rotate the shaft 33, the usual means being an electric motor. However, in case of failure of the electric current a crank 36 indicated by dot-and-dash lines in Fig. 1, enables the machine to be manually operated. The crank 36 is removably coupled to a pinion 37 journaled on a stud 38 projecting from the right side frame 34 of the machine. The pinion 37 meshes with a large gear 39 journaled on a stud 40 also projecting from the right side frame 34, the gear 39, in turn, meshing with a gear 41 fast on the drive shaft 33. The ratio of the gears 37, 39 and 41, is such that it requires two complete rotations, in clockwise direction, of the crank 36 to impart

one complete rotation in clockwise direction to the gear 39 and the drive shaft 33. The gear 39, however, completes only one-half of a rotation in counter-clockwise direction at 5 each adding operation of the machine, and one full turn in counter-clockwise direction at each total-taking operation of the machine.

Adjustment of the total control lever 30 in either direction from its normal or "add" 10 position with a consequent rocking of the disk 31, causes the walls of a cam slot 110 formed in the total control disk to shift a pin 106 carried by one arm of a multiple-armed lever 107 pivoted at 109, to rock the lever. An arm 15 112 also pivoted at 109 and having a pin and slot connection 111 with the multiple-armed lever 107, has a cam-shaped slot 115 formed therein to accommodate a pin 116 on an arm 117 fast on a suitably supported shaft 100. 20 A spring 114 extending between the multiple-armed lever 107 and the cam-slotted arm 112 normally holds these parts separated as far as the pin and slot connection 111 will permit.

A link 97 (Fig. 1) connects an arm 99 25 fast on the outer end of the shaft 100 with one arm of a lever 89 pivoted intermediate its ends at 90, the remaining arm of the lever 89 having a pin and slot connection with one end of a pitman 120 slidably mounted on the stud 40 on which the large driving gear 39 turns. The pitman 120 determines 30 whether or not the machine will make one or two cycles of operation.

A disk 118 journaled on the stud 40 just 35 behind the pitman 120 remains stationary during operations wherein the drive shaft 33 is to make but a single rotation, due to the disk 118 being held to the pitman 120 by a stud 119 on the pitman resting in a recess in 40 a cam slot 121 formed in the outer face of the disk 118.

A radially extending coupling slide 124 slotted to embrace the stud 40 lies in a diametrically extending groove 127 formed 45 across the back of the normally idle cam disk 118 and between the cam disk and the large drive gear 39, such coupling slide carrying a laterally projecting ear 123 at its outer end embraced between a pair of inwardly projecting studs 122 extending from the inner face of the pitman 120, the outer end of the coupling slide lying in line with a recess 125 formed in the large gear 39 when the machine is at rest.

50 So long as the total control lever 30—31 remains in its normal or "add" position, the linkage commencing with the multiple-armed lever 107 (Fig. 2) and terminating with the lever 89 (Fig. 1) maintains the pitman 120 and the coupling slide 124 in their normal idle positions, but adjustment of the total control lever 30—31 in either direction, as, for instance, to the first position below the "add" position, shown in dot-and-dash lines 55 in Fig. 2, operates through the linkage to

rock the lever 89 clockwise, to draw the pitman 120 and hence the coupling slide 124 outwardly radially of the cam disk 118 and large gear 39, to enter the projection 119 of the pitman into the cam groove 121 on the face of the disk 118 and simultaneously enter the outer end of the coupling slide 124 into that one of the recesses 125 which, at that time, lies in line therewith.

The extent of movement imparted to the pitman 120 by the total control lever 30, 31 when adjusted is always the same, due to the cam slot 110 (Fig. 2) in the total control disk 31, irrespective of the extent of adjustment of the total control lever, and is just sufficient to effect the coupling of the cam disk 118 to the large drive gear 39, but as the cam disk 118 completes the first half of its rotation, the cam groove 121 of the disk shifts the pitman 120 farther outward radially, the pitman being held at its outward limit of travel through nearly the remaining half of the rotation of the cam disk, after which it is returned to its intermediate position where it remains until the end of the rotation of the cam disk.

The pitman 120 carries a stud 126, and as it is shifted by the cam disk 118 to its extreme outer position, the pitman through the stud 126, shifts mechanism not pertinent to the present invention and hence not shown, which controls the application of power to the large drive gear 39 so as to disable the usual control mechanism until the large gear is given a single complete rotation. Return 100 of the pitman 120 to such intermediate position restores the rotation controlling mechanism (not shown) to position where it will become effective at the end of the complete rotation of the large gear 39. 105

The coupling slide 124, however, does not partake of the additional outward and inward travel of the pitman 120 under control of the cam disk 118, because rotating of the large drive gear 39 carries the ear 123 away 110 from between the pins 122 of the pitman 120 which is returned to its intermediate position in plenty of time to enable the ear to insert itself between the pins as the ear completes one counter-clockwise rotation. 115

Automatic restoration of the total control lever to normal position

As originally designed, the total control lever 30, 31 was manually adjusted to any 120 of its positions and remained where set until manually shifted to another position, but the United States Letters Patent of Samuel Brand, No. 1,736,067, disclosed means to automatically restore the total control lever 30, 31 to its normal or "add" position, from its first position below "add" back to its "add" or normal position.

Movement of the total control lever 30 from its "add" position to its first position 130

below the "add" position, as shown in dot-and-dash lines in Fig. 2, shifts a lug 42 projecting rearwardly from the control plate or disk 31, into the path of oppositely placed 5 rollers 43 and 44, rotatively mounted within an angular groove 45 (Fig. 5) formed in the periphery of a restoring collar 46 journaled on a shaft 47 supported in the side frames 34 and 35.

10 A segmental gear 55 fast on a short shaft 56 journaled in a bracket 57 (Fig. 1), extending downwardly from a back frame 58 secured to the machine side frames 34 and 35, meshes with a partial gear 59 (Figs. 2, 4 and 5) loosely mounted on the shaft 47 adjacent the restoring collar 46. A strong spring 60 (Fig. 1) attached to an arm 61 secured to the other end of the short shaft 56, constantly urges the shaft and the toothed segment 55 20 in clockwise direction to the position shown in Figs 2 and 4, in which the parts are arrested by contact of the laterally turned end of the arm 61 (Fig. 1) with the back plate 58. A spring 62, (Fig. 5) coiled about the 25 shaft 47, constantly presses the partial gear 59 axially against the adjacent end of the collar 46, to normally maintain the driving lugs 63 projecting from the hub of the partial gear 59 within notches 64 in the adjacent 30 edge of the restoring collar 46.

35 A hooked tensioning link 82 (Fig. 1) pivotally connected to the arm 61, depends to a point adjacent a stud 81 mounted on a lever 72 pivoted at 73 to the side frame 34, and when the machine is operated, under certain 40 adjustments, this stud is adapted to engage the hook 83 to pull the tensioning link 82 downwardly and rock the arm 61, shaft 56 and toothed segment 55 to rotate the partial gear 59 and tension the spring 60.

45 A cam 70 turning with the drive shaft 33, is adapted, in its rotation, to wipe against a roller 71 on the lever 72 at each operation of the machine, to rock the latter in clockwise direction against the tension of a strong return spring 74 which maintains the roller 71 in contact with the cam 70 at all times.

50 The nodal point of the cam normally lies just beyond the roller 71, and as the shaft 33 makes a single complete rotation at each adding operation, and two rotations at each totaling and sub-totaling operation, the cam 70 will rock the lever 72 with its stud 81 clockwise near the end of each rotation and 55 the spring 74 will restore the lever in counter-clockwise direction to normal just as or immediately after the shaft completes its rotation.

59 But the hook 83, although embraced between the free end of the lever 72 and a guide arm 80, normally lies outside the path of travel of the stud 81 so long as the total control lever 30, 31 occupies its normal "add" position, being held in such idle position by 65 a restraining link 85 slidably supported on

a guide stud 86 intermediate its ends, one end of the restraining link 85 having an open latch 84 releasably hooked over a pin 91 on the tensioning link 82, and the opposite end of the restraining link 85 having an inclined slot to encircle a stud 87 carried on one arm of the lever 89 constituting part of the linkage between the total control lever 30, 31 and the pitman 120.

70 A spring 92 tends to draw the restraining link 85 to the left (Fig. 1), but so long as the total control lever 30, 31 remains in its "add" position, it will retain the lever 89 in the position shown in Fig. 1, which last-named lever will maintain the restraining link 85 at the right hand limit of its travel to hold the hooked link 82 in idle position disconnected from the rocking drive lever 75 2.

75 The total control lever 30, 31, is adjusted prior to the operation of the machine and when set to its first position below its "add" position, operates the linkage previously described, terminating in the lever 89 to rock the latter clockwise and cause the pitman 120 80 to shift the coupling slide 124 to effective 90 position.

85 The stud 87 carried by the lever 89 rocks to the left to enable the spring 92 to draw the restraining link 85 to the left (Fig. 1), and with it, the hooked link 82.

90 The advance of the hooked link 82 is not sufficient at this time, to locate the hook 83 beneath the stud 81 towards which it advances.

100 The machine being now set for a total taking operation, the crank 36 is operated to turn the pinion 37, the large gear 39 and the gear 41 on the drive shaft 33, and due to the coupling slide 124, the large gear 39 carries the cam disk 118 along with it, the projection 119 of the pitman 120 lying in the cam groove 121 of the cam disk.

105 It will be remembered that the large gear 39 and its cam disk 118 make one complete rotation on total taking operations and as a consequence the drive gear 41 and the drive shaft 33 with its cam 70 make two complete rotations.

110 The cam 70, shortly after the beginning of its first rotation, starts to depress the drive lever 72, but since the restraining link 85, at this time, still holds the hook 83 apart from the stud 81 on the lever 72, the lever moves idly downward, and at the end of the first rotation the tensioned spring 74 snaps the lever back to its normal position as the high point of the cam 70 escapes the roller 71 on the lever.

115 However, just prior to the return of the drive lever 72 to its normal position, the cam groove 121 imparts the second step of movement to the pitman 120, advancing it radially outward to its fullest extent, and the pitman, in turn, imparts a further step of 120 125 130

clockwise travel to the lever 89 which enables the spring 92, operating upon the restraining link 85, to draw the hooked link 82 into the path of the stud 81 on the drive lever 72 which, at this time, is located some distance beneath the hook 83.

Consequently, the lever 72, as it returns to its normal position under the influence of the spring 74 at the end of the first rotation 10 of the cam 70, causes the stud 81 to strike the inclined face 93 and rock the hooked link counter-clockwise against the tension of the spring 92 which immediately restores the hooked link to its adjusted position with 15 its hook 83 beneath the stud 81 as soon as the stud passes the hook. The slot and pin connection 87 between the restraining link 85 and the lever 89 permits relative motion between the link and lever for this purpose.

20 The cam groove 121 continuing to hold the pitman 120 at its limit of outward travel, the cam 70 on the drive shaft 33, as it starts on its second cycle of rotation, depresses the drive lever 72 and its stud 81, which latter 25 contacts the hook 83, drawing the link 82 downwardly to rock the arm 61, shaft 56 and toothed segment 55 counter-clockwise.

The toothed segment, being meshed with the partial gear 59, turns the latter clockwise. The teeth 63 (Fig. 5) on the hub of the partial gear, due to their pitch, ratchet idly over the co-acting recesses 64 on the hub of the total lever restoring collar 46 during the clockwise rotation of the partial 30 gear. A dog 65 pivoted at 66 on the side frame 34, holds the restoring collar 46 against clockwise rotation at this time, which might be induced by the friction between the hub of the partial gear and the collar 35 due to the pressure of the spring 62 encircling shaft 56, a spring 67 holding the nose of the dog in engagement with one of the notches 69 in the hub of the restoring disk.

The toothed segment 55 carries a stud 95, 40 which contacts the tail 96 of the dog 65 just as the toothed segment completes its counter-clockwise travel, to disengage the nose of the dog from the notch 69 to free the restoring collar 46 for operation.

50 Meanwhile, as the drive lever 72 rocks clockwise under the influence of the cam 70 on the drive shaft 33, to draw the hooked tensioning link 82 downwardly and tension the drive spring 60, the pin 91 of the tensioning 55 link 82 is withdrawn from the throat of the latch 84 which is cut away or beveled off, as at 94 for clearance and to form a guiding surface for the pin 91 as hereinafter appears.

60 As the large drive gear 39 and the cam disk 118 approach the end of the second cycle of rotation in a totalizing operation, the cam groove 121 shifts the pitman 120 inwardly to its intermediate position, as a result of which, 65 the pitman rocks the lever 89 counter-clock-

wise to its intermediate position. On this partial return movement, the stud 87 partially returns the restraining link 85 towards its normal position, but since, at this time, the lever 72 has drawn the tensioning link 70 82 and its pin 91 downwardly so that the latter lies opposite the clearance face 94 of the restraining link, this link exercises no influence upon the tensioning link which remains hooked under the stud 81 of the drive lever 72, 75 until the spring 74 restores the lever 72 to its normal raised position.

The drive spring 60 causes the tensioning link 82 to accompany the lever 72 on its return, the pin 91 on the tensioning link 82 80 contacting the beveled clearance face 94 on the restraining link 85, which, being held against movement at this time, shunts the pin 91 and the link towards the right to and into the throat of the latch 84.

The drive spring 60, in drawing the tensioning link 82 upwardly, rocks the arm 61, shaft 56 and toothed segment 55 in clockwise direction to turn the partial gear 59 counter-clockwise, whereupon the abrupt 90 sides of that tooth 63 on the hub of the partial gear which is entered in the notch 64 of the restoring collar 46, turns such collar counter-clockwise and with it the rollers 44 mounted in the peripheral groove of the collar. 95

As previously explained, the manual adjustment of the total control lever 30, 31 from its "add" position to its first total taking position below the "add" position turns the total control plate 31 to introduce the peripheral lug 42 thereof into the peripheral groove 45 of the restoring collar 46. 100

Hence the collar, on its counter-clockwise rotation, brings one of the rolls 43, 44 into 105 contact with the lug 42 to restore it, together with the total control disk 31, and its control lever 30 to the normal or "add" position.

The faced end of the arm 61 striking the inner side of the back frame 58, arrests the farther travel in clockwise direction of the toothed segment 55, which latter, as it returns to normal position, withdraws the stud 95 from the tail of the dog 65 to release the dog to the action of its spring 67 which rocks the nose of the dog into contact with the hub of the collar so that in the rotation of the collar, as soon as a notch 69 is brought beneath the nose, the dog will drop in to lock the collar against clockwise rotation on the next operation of the machine. 115

The total control lever 30, 31 on its automatic return to its normal "add" position, causes the wall of its cam slot 110 (Fig. 2) to operate the linkage controlled thereby including the lever 89, to which is imparted its final step of counter-clockwise travel, the lever, in turn, restoring the pitman 120 to its normal position with its pin 119 in the seat in the inner wall of the cam groove 121. The 120 125 130

pitman, on its restoration, disengages the coupling slide 124 from the large gear 39 and sets the mechanism (not shown) which prevents further operation of the machine.

5 If, prior to the operation of the machine, the total control lever 30, 31 is moved to any other position excepting the first position below the "add" position, the restoring mechanism will operate idly since the lug 42 is not 10 in the path of the roller 43. Thus, the total lever will only be returned to its home position from the first position below the "add" position.

15 The bank of transaction keys and the differential mechanism controlled thereby are old in the U. S. Letters Patent to Fuller, No. 1,242,170, and to Shipley, No. 1,619,796, heretofore mentioned, to which reference may be had for a full and complete disclosure of 20 this mechanism. However, for a complete understanding of the present invention, a brief description of the key bank and differential controlled thereby follows.

25 The transaction keys 145 (Fig. 3) are slidably mounted in the usual key frame 146 supported in the machine on cross rods 147 and 148 extending between the machine side frames 34 and 35. A detent bar 149, suitably mounted in the key frame 146 cooperates with key pins on the keys 145 to retain the keys in their depressed positions. When, 30 towards the end of the operation of the machine, the depressed key is released by mechanism (not shown herein) the key depressed is restored to its outward position.

35 Operation of the main drive shaft 33 in clockwise direction rotates a pair of cams 162, 163 fast thereon. These cams rock a bell crank 164 journaled at 165 on a hanger 40 155 of a pair of hangers fixed in the machine, to rock the bell crank first clockwise and then counter-clockwise. A link 166 connects the bell crank with a shouldered driving sector or actuator 161 journaled on a stud 154 extending 45 between the hangers 155, one only of which is shown, so that the driving sector is rocked through a constant path of travel first clockwise and then counter-clockwise at each operation of the machine.

50 A differentially adjustable arm 153 journaled on the stud 154 is slotted at its outer end to accommodate a stud 156 projecting from one arm of an elbow lever 157 pivoted at 144 to the outer end of a second differentially adjustable arm 160 also journaled on the stud 156 parallel with the arm 153 and this elbow lever 157, together with a link 158 mounted on the arm 160, unite in supporting a latch 159 which normally connects 55 the differentially movable arms 153 and 160 with the invariably movable actuator 161.

60 The differentially adjustable arms 153, 160 normally lie at their extremes of counter-clockwise travel, the latch 159 connecting 65 them with the actuator, and a spring-pressed

zero stop pawl 150 fast on a short shaft 151 journaled in a depending ear of the key frame 146, normally lies in the path of the free end of the differentially movable arm.

66 Depression of any one of the keys 145 rocks the zero stop pawl 150 to its ineffective position out of the path of the differential arm 153. Depression of any one of the keys 145 interposes its inner end in the path of the elbow lever 157. The actuator 161, because 70 of its latch connection 159 with the differential arms 153, 160 carries the differentially movable arms therewith on its clockwise travel until the forward end of the elbow lever 157 strikes the inner end of the depressed key, whereupon continued movement of the actuator rocks the elbow lever 157 counter-clockwise to draw the latch 159 out of cooperative relation with the actuator 161 and thrusts the nose of the latch into one 75 of a succession of notches 167 in a serrated plate 168 secured to the inner face of the key frame adjacent the inner ends of the keys. The actuator 161 completes its invariable excursion and on its counter-clockwise return movement, as the shoulder in the actuator 161 arrives opposite the foot of the latch 159, a spring 169 draws the latch out of the notch 167 and engages the righthand end thereof with the shoulder on the actuator 161 to disconnect the latch from the keyboard. 80 At the same time, a face 170 of the actuator 161 engages a stud 171 projecting from the differentially movable arm 160 and restores the arms 153, 160 to their normal positions 85 as viewed in Fig. 3. The differentially movable arm 160 variously positions the left-hand end of a beam 180 pivotally connected thereto, and having its right hand end bifurcated to straddle a stud 181 in a link 182. The lower end of the link is pivotally connected to a type carrier adjusting arm 183 journaled on a shaft 184 turning in bearings in the side frames 34 and 35, and the upper end of the link is pivotally connected to an aligner segment 185 fast on the shaft 136. The differential movement of the differentially movable arm 160 under the control of the transaction keys 145 differentially adjusts the left 90 hand end of the beam 180 accordingly. On the clockwise travel of the bell crank 164, a roller 186 thereon contacts the lower edge of the beam 180 to complete the adjustment thereof if necessary. The differential movement of the beam 180 is transmitted by the link 182 to the arm 183, to set mechanism in the printer (not shown) but which is disclosed in the above-mentioned patent, and to set the indicator aligning segment 185 to a 95 position corresponding to the particular key depressed. This segment 185 is provided with teeth 190, the purpose of which is to set indicators, (not shown herein) but which are fully disclosed in the above-mentioned patent.

An aligner bar 191 supported on a plurality of arms 192, only one of which appears in the drawings, which are fast on an aligner shaft 193 journaled in the frames 34-35, operates with serrations on the aligner segment 185 to align the segment 185, link 182 and the arm 183 in the positions to which they are adjusted. Any suitable mechanism may be employed to operate the aligner shaft 193.

In the machine as disclosed in the U. S. patent of Samuel Brand, Number 1,736,067, the total lever restoring mechanism functions to restore the total control lever to its normal position from its first position below the "add" position at the end of each totalizing operation, regardless of which of the transaction keys are depressed. However, as heretofore explained, it is desirable to disable the total control lever restoring device when resetting certain of the totalizers to zero, and to this end, mechanism now to be described, is adjusted under the control of certain, at least, of the bank of transaction keys (Fig. 3), to disable the total control lever restoring mechanism when the machine is operated with such transaction keys depressed.

This disabling mechanism may conveniently comprise a bolt 130 (Fig. 1) slidably mounted on guide studs 131 and 132 projecting from the right side frame 34 of the machine. A stud 133 near the upper end of the link 130 projects through an aperture 134 in the right side frame 34 to cooperate with a finger 135 fast on the shaft 136 which is differentially rotated under the control of the transaction keys. The ends of the shaft 136 are tapped out and journaled on trunnion studs 137, the heads 138 (Fig. 1) of which are secured to the side frames 34 and 35. Only one of the trunnion studs 137 appears in the drawings, the other being on the opposite side of the frame 35 (Fig. 3). The shaft 136, finger 135 and bolt 130 are shown in Fig. 1 with the differential mechanism in the "zero" position. Upon an operation of the machine, the differential mechanism, under control of the "1" key, rocks the finger 135 one step in clockwise direction to lower the bolt 130. This movement, however, is not sufficient to enter a lug 139 formed on the lower end of the bolt 130 into a recess in the upper edge of the link 85. However, when the differential mechanism is operated under the control of the transaction keys in the "2" to "9" positions inclusive, the finger 135 rocks a corresponding number of steps farther in clockwise direction to permit the spring 129 to lower the bolt 130 a greater extent, to enter the lug 139 in the recess 140 in the restraining link 85. The bolt 130 needs to operate but two steps before its lug 139 seats itself in the recess 140, after which the finger 135 merely rocks idly in clockwise direction away from the stud 133 when transaction keys in the "3" to "9" positions, inclusive, have been

depressed. Under such adjustment of the transaction keys, it is seen that, when the total control lever 30 is shifted from its "add" position to its first totalizing position below the "add" position, to rock the lever 89 (Fig. 1) through its initial movement or step in clockwise direction, the spring 92 causes the restraining link 85 to follow until the right hand wall of the recess 140 in the link contacts the lug 139 on the lower end of the bolt 130, which arrests the restraining link 85 while the latter is still effective to hold the tensioning link 82 with its hook 83 out of the path of the stud 81, and since the bolt 130 remains in this position throughout the totalizing operation, the links 85 and 82 will also be retained in their respective positions, just described, throughout the operation to prevent the drive lever 72 from lowering the tensioning link 82 to cock the total lever restoring mechanism which, therefore, remains ineffective to restore the total control lever 30, 31 at the end of the operation. The recess 140 in the restraining link 85 is of sufficient length to enable the link to advance under the influence of its spring 92, relatively to the lug 139, to rock the hooked tensioning link 82 through its first step or movement in which its hook 83 still remains out of the path of the stud 81, when the total control lever 30, 31 is rocked out of its "add" position. But the lug 139 withdraws the restraining link in its intermediate effective position, the automatic rocking of the lever 89 through its second step of clockwise travel operating to shift its stud 87 along the slot in the restraining link 85. The stud 87 restores the restraining link 85 to the limit of its travel towards the right, under this arrangement, only when the total control lever 30, 31 is manually restored to its normal "add" position.

If the totalizer from which the total is to be taken, is selected under the control of the transaction key 145 in the "1" position, the finger 135 holds the bolt 130 out of the recess 140 to enable the automatic restoring device for the total control lever 30, 31 to function at the end of the operation. But if the totalizer is selected under the control of the "2" to "9" keys, inclusively, the differential mechanism rocks the finger 135 out of contact with the stud 133 permitting the spring 129 to urge the lug 139 into the recess 140 to disable the automatic restoring mechanism.

Modified control

A modification of the transaction key control is illustrated in Fig. 6 of the drawings.

In this form of control, a stud 195 projecting from the upper end of a bolt 196 mounted to slide on guide studs 197 and 198 projecting from the side frame 34 of the machine, projects through an opening (not shown) in the frame and cooperates with a recessed control disk 199 fast on the shaft 130

136 and differentially rotatable therewith under the control of the transaction keys 145, as heretofore explained. The control disk 199 may be differentially adjusted to a 5 number of positions equal to the number of transaction keys plus one, which is the "zero" position. When the machine is operated, the control disk 199 rotates to bring the position on the periphery thereof corresponding 10 to the key depressed beneath the stud 195 in the bolt 196. This bolt operates in the same manner as does the bolt 130, heretofore explained, to disable the automatic restoring means for the total lever, the bolt 15 having a projection 200 which may be accommodated in the recess 140 in the restraining link 85. In this modified form, the periphery of the control disk 199 is recessed according to a predetermined plan, so that 20 when one of the recesses is positioned beneath the stud 195, a spring 201 draws the bolt 196 downwardly to insert the projection 200 thereon into the recess 140 and prevent the tensioning link 82 from moving beneath the stud 81 of the drive lever 72, thus 25 preventing the automatic restoration of the total lever to its normal "add" position at the end of the operation of the machine.

While the form of mechanism herein 30 shown and described is admirably adapted to fulfill the objects primarily stated, it is to be understood that it is not intended to confine the invention to the one form or embodiment herein disclosed, for it is susceptible 35 of embodiment in various forms all coming within the scope of the claims which follow.

What is claimed is:

1. In a machine of the class described, a 40 total control member adjustable from one position to another; means to automatically restore the total control member to the position from which it was adjusted; means to condition the automatic restoring means 45 for actuation; a manipulative device; and means controlled thereby to render the conditioning means ineffective.

2. In a machine of the class described; the 50 combination with a total control member adjustable from one position to another; means to automatically restore the total control member to the position from which it was adjusted; and means controlled by the total control member to render the automatic restoring means effective; of a plurality of 55 manipulative devices; and means controlled thereby to control the effectiveness of the automatic restoring means.

3. In a machine of the class described, the 60 combination with a total control member adjustable from one position to another; of means to automatically restore the total control member to the position from which it was shifted; means controlled by the total 65 control member to render the automatic re-

storing means effective; a plurality of manipulative members; and means controlled thereby to control the effectiveness of the means controlled by the total control member.

4. In a machine of the class described, the 70 combination with a total control member adjustable from one position to another; drive means; means operable by the drive member to automatically restore the total control member to the position from which it was shifted; means controlled by the total control member to enable the drive means to operate the automatic restoring means; a manipulative member; and means controlled thereby to control the effectiveness of the enabling means.

5. In a machine of the class described, the 75 combination with a total control member adjustable from one position to another; drive means, means operable by the drive means to automatically restore the total control member to the position from which it was shifted; means controlled by the total control member to connect the automatic restoring means with the drive means; a manipulative device; and means controlled by the manipulative device to control the effectiveness of the connecting means.

6. In a machine of the class described; the 80 combination with a plurality of manipulative devices; means differentially positioned under the control of said devices; a total control member adjustable from one position to another; means to automatically restore the total control member to the position from which it is shifted; a drive member for the automatic restoring means; means to connect the automatic restoring means with the drive member; and means operable under the control of the differentially positioned means to control the connection of the automatic restoring means and the drive member.

7. In a machine of the class described; the 85 combination with a total control member adjustable from one position to another; of means, controlled by the total control member and having effective and ineffective positions, to automatically restore the member to one of its positions when the said means is in its effective position; and differentially controlled means to retain the restoring means in ineffective position irrespective of the total control member.

8. In a machine of the class described; the 90 combination with a total control member adjustable from one position to another; of means to automatically restore the total control member to one of its positions; mechanism controlled by the total control member to render the restoring means effective; a manipulative device; and means controlled by the manipulative device to control the effectiveness of the mechanism controlled by the total control member.

9. In a machine of the class described; the combination with a manipulative device; and a total control member adjustable from one position to another; of means to automatically restore the total control member to one of its positions; means to drive the automatic restoring means, the drive means and the automatic restoring means being normally disconnected; means under control of the total control lever to connect the automatic restoring means and its drive means; and means under the control of the manipulative device to render the connecting means ineffective to connect the automatic restoring means and the drive means.

10. In a machine of the class described; the combination with a plurality of manipulative devices; and a total control member adjustable from one position to another; of means to automatically restore the total control lever to one of its positions; means to drive the automatic restoring means, the automatic restoring means being normally disconnected from the drive means; means under the control of the total control member to connect and disconnect the automatic restoring means and its drive means, a bolt to render the connecting means ineffective; and means differentially controlled by the manipulative devices to control the effectiveness of the bolt.

11. In a machine of the class described; the combination with a plurality of manipulative devices; and a total control member adjustable from one position to another; of means to automatically restore the total control member to one of its positions; means to drive the automatic restoring means, and normally disconnected therefrom; a link under the control of the total control member to connect the automatic restoring means with the drive means, the link being recessed; a bolt having a projection to enter the recess in the link to prevent connection of the automatic restoring means and the drive means; and means controlled by the manipulative devices to control the effectiveness of the bolt.

12. In a machine of the class described, the combination with a plurality of manipulative devices; and a total control member adjustable from one position to another; of means to automatically restore the total control member to one of its positions; means to drive the automatic restoring means, and normally disconnected therefrom; means controlled by the total control member to connect the automatic restoring means with the drive means; means cooperable with the last-named connecting means; and means controlled by the manipulative devices, and having a plurality of positions, to control the cooperable means to enable such cooperable means to restrain the connecting means in ineffective position.

13. In a machine of the class described; the combination with a plurality of manipulative devices; and a total control member adjustable from one position to another; of means to automatically restore the total control member to one of its positions; means to drive the automatic restoring means, the automatic restoring means being normally disconnected from its drive means; a link movable under the control of the total control member to effect the connection of the automatic restoring means to its drive means; and a bolt movable under the control of the manipulative devices to prevent the link from effecting said connection.

14. In a machine of the class described, the combination with a total control member adjustable from one position to another; drive means; means operable by the drive means to automatically restore the total control member to one of its positions; means to retain the automatic restoring means disconnected from its drive means; means controlled by the total control member to operate the retaining means; of means to hold the retaining means effective regardless of the total control member, with provision for play between the holding means and the retaining means to enable the adjustment of the total control member relatively to the holding means; and a manipulative device to control the effectiveness of the holding means.

15. In a machine of the class described, the combination with a total control member adjustable from one position to another; drive means; and means operable by the drive means to automatically restore the total control member to one of its positions; of means to retain the automatic restoring means disconnected from its drive means, the retaining means having a recess formed therein; means controlled by the total control member to operate the retaining means; a bolt removably entered in the recess in the retaining means to hold the retaining means effective regardless of the total control member; the retaining means adapted to have movement relatively to the bolt equal to the excess length of the slot over the width of the bolt, to enable the adjustment of the total control member relatively to the bolt; and a manipulative device to control the effectiveness of the bolt.

16. In a machine of the class described, the combination with a total control member adjustable from one position to another; drive means; and means operable by the drive means to automatically restore the total control member to the position from which it was shifted, the automatic restoring means being normally disengaged from its drive means; of a bolt to control the engagement of the automatic restoring means and the drive means; a manipulative device; and

means associated therewith to control the effectiveness of the bolt.

17. In a machine of the class described, the combination with a total control member adjustable from one position to another; drive means; and means operable by the drive means to automatically restore the total control member to the position from which it was shifted; a restraining member to hold the automatic restoring means and its drive means disengaged; and means controlled by the total control member to operate the restraining member; of a bolt cooperable with the restraining member to retain it effective regardless of the adjustment of the total control member; and a manipulative device to control the effectiveness of the bolt.

18. In a machine of the class described, the combination with a total control member adjustable from one position to another; drive means; and means operable by the drive means to automatically restore the total control member to the position from which it was shifted; the automatic restoring means being normally disengaged from its drive means; means controlled by the total control member to enable the engagement of the automatic restoring means and the drive means; means to control the operation of the engagement enabling means, regardless of the adjustment of the total control member; and a manipulative device to control the effectiveness of the last-named control means.

19. In a machine of the class described, the combination with a total control member adjustable from one position to another; means to automatically restore the total control member to the position from which it was shifted; and means controlled by the total control member to render the automatic restoring means effective; of a blocking device to retain the automatic restoring means ineffective regardless of the adjustment of the total control member; and manually set means to control the effectiveness of the blocking device.

20. In a machine of the class described, a total control member adjustable from one position to another; means to automatically restore the total control member to the position from which it was adjusted; means to condition the automatic restoring means for actuation; a manipulative device; and means controlled thereby to render the conditioning means ineffective, the last means including a notched disc positioned under control of the manipulative device.

In testimony whereof I affix my signature.
FRIEDRICH W. F. BERGER.
